MANUFACTURE OF PEN POINTS

George E. Bartol, Jr., Wynnewood, Pa., assignor to
 C. Howard Hunt Pen Company, Camden, N. J.,
 a corporation of New Jersey

Application December 31, 1936, Serial No. 118,464

3 Claims. (Cl. 113—32)

This invention relates to the manufacture of pen nibs or points, and the invention has particular reference to the provision of an open slot in the toe part of the pen.

- 5 The primary object of the invention is to simplify and improve a fabrication method, providing for initial slitting of the toe of a pen to form nib parts, and subsequent opening of the slit to form a slot.
- 10 The invention constitutes an improvement on the process disclosed in the copending application of Lloyd S. Henwood, Serial No. 4,813, filed February 4, 1935, assigned to the assignee of this application.
- 15 The full nature of the invention, and more specific objects and advantages will appear to better advantage from a consideration of the following description referring to the accompanying drawing, in which—
- 20 Figure 1 is a plan view of a stamped blank from which a pen may be formed in accordance with the process of this invention;

Figure 2 is an end view taken from the right of Figure 1 but illustrating the blank after the performance of a bending operation hereinafter described;

Figure 3 is an under-side view of the blank after the slitting operation;

Figure 4 is an under-side view of the blank as shown in Figure 3 following an additional step in the process;

Figure 5 is a cross-sectional view taken as indicated by the section line 5—5 on Figure 4 and additionally showing portions of tools employed in the treatment of the blank; and

Figure 6 is a top plan view of the completed pen.

Referring first to Figure 1, the blank is preferably stamped out of suitable sheet metal stock and has a heel part 7 and a toe part 8, the latter, if desired, being provided with tabs adjacent the writing tip as shown at 9. The blank may also be pierced as at 10 adjacent the base of the toe part 8, although it should be understood that this piercing is not essential to the invention.

Following stamping, the tabs 9 are preferably bent along lines substantially coinciding with the marginal outline of the pen into approximately parallel and adjacent positions as shown at 9a in Figure 2, and in the next step of the process (shown in Figure 3) the toe part of the pen is slit as at 11, the slit being extended from the pierce hole 10 to the writing tip of the pen between the adjacent bent tabs 9a. This slitting may conveniently be performed by a shearing

operation which, for practical purposes, removes no metal.

To open the slit and thus form a slot for improving ink flow from the region of the upper end of the slit or of the pierce hole 10 (where this is employed) downwardly to the writing tip, the region of the pen adjacent to and above the pierce hole 10 is thinned by the action of co-operating die elements, this thinned region being indicated by the shaded area 12. This thinning (particularly if the degree thereof is substantially uniform throughout the entire area 12, or if the area 12 is relatively restricted and not extended to the extreme heel end of the pen) has a tendency to open the slit 11 into a slot which is wider at the writing tip of the pen than in the region of the inner end of the slit.

In order to overcome this effect, the present invention provides for thinning the metal of the two nib parts formed at opposite sides of the slit in regions such as indicated, for example, at 13 in Figure 4. The result of this is to swing the two nib parts toward each other. This may be accomplished by the use of simple die press members including a block or anvil 14 (see Figure 5) and cooperating relatively reciprocable forming members 15 arranged to strike the areas 13.

Preferably, all of the forming tools, i. e., those for swaging or working the metal in region 12 as well as in regions 13—13, are mounted and operated simultaneously in a single press or equivalent machine, and from careful inspection of Figure 4 it will be seen that the result of this treatment is the production of a slot the edges of which may be slightly divergent from the pierce hole to a point intermediate the areas 13—13, as shown at 16; and the edges of which slot, as shown at 17, are substantially parallel from the point intermediate regions 13—13 to the writing tip. If desired, the extent of swaging in areas 13—13 may be such as to cause the edges in the region 17 to converge again toward the tip. However, this may only be required with some types of pens, and in either event, after the foregoing working, the pen is "raised", i. e., bent to a rounded shape, and during this operation the nib parts are bent so as to bring the tips thereof adjacent to or in contact with each other and thus close the slot at the writing tip, as may clearly be seen from inspection of Figure 6 illustrating the pen in completed form.

The foregoing, I have found, constitutes a highly effective method of opening a slit to form a slot, which slot is closed at the writing tip and not unduly divergent in any part thereof. This

desirable result is also achieved with a minimum of thinning of the metal of the pen in any one region.

I claim:—

- 5 1. In the manufacture of pens, the steps of forming a pen blank, slitting the toe of the blank to form nib parts, opening the slit to form a slot by thinning the metal of the blank in a zone located adjacent the inner end of the slit, and 10 thinning the metal of the blank in two additional zones located one on each nib part intermediate the ends of the slit.
- 15 2. In the manufacture of pens, the steps of forming a pen blank, slitting the toe of the blank to form nib parts, opening the slit to form a slot by thinning the metal of the blank in a zone located adjacent the inner end of the slit, thinning the metal of the blank in two additional zones

located one on each nib part intermediate the ends of the slit, the thinning being effected in a manner to produce a substantially parallel edged slot in the region between the tip of the blank and said zones located on the nib parts, and 5 thereafter bending the nib parts to close said slot at the tip of the pen.

3. In the manufacture of pens, the steps of forming a pen blank, slitting the toe of the blank to form nib parts, opening the slit to form a slot 10 by bodily displacing the nib parts from each other in the plane of the blank, and at least in part closing the slot toward the writing tip of the blank by thinning the metal of the blank in a region located adjacent the outer side edge of 15 each nib part.

GEORGE E. BARTOL, JR.
